JOHN E. BLACK, OF RUMSON, NEW JERSEY, ASSIGNOR TO THE BABCOCK & WILCOX COMPANY, OF BAYONNE, NEW JERSEY, A CORPORATION OF NEW JERSEY

STEAM TEMPERATURE REGULATOR

Application filed April 22, 1930. Serial No. 446,270.

This invention relates to a novel and improved steam temperature regulator, the novel features of which will be best understood from the following description and in the annexed drawing in which the single figure shows a fragmentary elevation of a portion of a boiler and the regulating device associated therewith. This figure is somewhat diagrammatic in character and parts are shown in section.

The boiler casing is indicated at 1, the details of the boiler having no bearing upon this invention, and therefore not being further illustrated. The boiler is, however, provided with the usual water space and steam space. The normal water line may occur in a steam and water drum 2. Steam generated in the boiler may be superheated in the usual way and conducted through a steam pipe 3 to the regulator 4. As shown on the drawing, this steam pipe has a vertically extending portion 5 and a horizontally extending portion 6, the regulator being connected to the portion 6 and located below the normal water line.

The regulator may be of any suitable form, but is here shown as comprising a chamber 7 through which pass a plurality of steam tubes 8 connected at their opposite ends to an inlet 9 and an outlet 10, respectively. The inlet and outlet may be separated by a diaphragm 11 and may conveniently be incorporated in one of the legs of a T-connection, the other two legs of which form part of the horizontal portion 6 of the steam pipe. In this way, steam may be passed from the pipe through the inlet and tubes back through the outlet into the steam pipe.

The chamber 7 is designed to contain water in order to temper or regulate the temperature of the steam passing through the tubes 8, the amount of heat absorbed by the water varying with the level of the water in the chamber, it being understood that this level may vary widely and in fact may be such that all tubes are completely covered.

In the form shown, the chamber is supplied with water from the steam and water drum by means of a downcomer 12 and a riser 13 connected respectively to the water space and steam space of the drum 2. By this means, a

circulation may be maintained, the water heated in the regulator tending to rise in the connection 13. In order to control the level of water in the regulator, a thermostat 14 of any suitable form may be placed in the steam pipe beyond the regulator, and this thermostat is joined by a suitable connection 15 to a valve 16 which will thus control the flow of fluid through the connection 13 to the steam space of the drum 2. In this way, the level of water in the regulator will be controlled. Preferably, the valve 16 is so arranged that if, for any reason, the thermostat should not operate, the valve will nevertheless remain open, thus assuring continued circulation through the regulator, which circulation in turn prevents the temperature of the steam from the superheater reaching an undesirably high point.

According to my invention, I provide a third connection 17, this connection leading from the lower part of the chamber 7, which part will normally contain water, to the water space of the drum 2. Preferably, this connection 17 is arranged in close proximity to some part of the boiler which is sufficiently hot to impart heat thereto and, in this form, I have shown the connection as being closely adjacent the superheated steam pipe 3, which will thus impart heat to the connection and cause a circulation of water upward in the connection 17 and downward in the connection 12. This circulation will take place most actively when the valve 16 is partially or entirely closed, and will relieve pressure on the regulator, and also will prevent excessive concentration of the water in the regulator. In order to insure proper circulation in the right direction, I provide a check valve 18 of any suitable form, which will permit flow in the direction indicated by the arrows, but will prevent flow in the opposite direction. This valve may be provided with the usual adjusting means 19, to regulate the flow.

I claim:

1. In combination, a boiler having a steam space, a superheated steam pipe, a temperature regulator connected to said pipe and having a chamber beneath the normal water level of the boiler, means for maintaining a

supply of water in the chamber, means for passing the steam from the pipe through the chamber while maintaining it out of contact with the water therein, a connection from the upper part of said chamber to said steam space, two connections from the lower part of the chamber to the water space of the boiler, and means for causing a circulation through said water connections and chamber.

2. In combination, a boiler having a steam space, a superheated steam pipe, a temperature regulator connected to said pipe and having a chamber beneath the normal water level of the boiler, means for maintaining a supply of water in the chamber, means for passing the steam from the pipe through the chamber while maintaining it out of contact with the water therein, a connection from the upper part of said chamber to said steam space, two connections from the lower part of the chamber to the water space of the boiler, means for causing a circulation through said water connections and chamber in one direction, and a check valve in one of the water connections preventing circulation in the opposite direction.

3. In combination, a boiler having a steam space, a superheated steam pipe, a temperature regulator connected to said pipe and having a chamber beneath the normal water level of the boiler, means for maintaining a supply of water in the chamber, means for passing the steam from the pipe through the chamber while maintaining it out of contact with the water therein, a connection from the upper part of said chamber to said steam space, two connections from the lower part of the chamber to the water space of the boiler, and means for applying heat to one of said water connections.

4. In combination, a boiler having a steam space, a superheated steam pipe, a temperature regulator connected to said pipe and having a chamber beneath the normal water level of the boiler, means for maintaining a supply of water in the chamber, means for passing the steam from the pipe through the chamber while maintaining it out of contact with the water therein, a connection from the upper part of said chamber to said steam space, two connections from the lower part of the chamber to the water space of the boiler, means for applying heat to one of said water connections, and a check valve in said heated water connection permitting flow to said water space but preventing flow therefrom.

5. In combination, a boiler having a steam space, a superheated steam pipe, a temperature regulator connected to said pipe and having a chamber beneath the normal water level of the boiler, means for maintaining a supply of water in the chamber, means for passing the steam from the pipe through the chamber while maintaining it out of contact

with the water therein, a connection from the upper part of said chamber to said steam space, two connections from the lower part of the chamber to the water space of the boiler, one of said water connections being disposed closely adjacent a portion of said steam pipe, whereby the water in said connection will be heated to cause it to flow to the boiler.

6. A device for regulating the temperature of superheated steam comprising, in combination, a regulator chamber, a conductor guiding superheated steam through the chamber, a steam pipe discharging superheated steam into the conductor, a discharge pipe leading superheated steam from the conductor, circulating means including a tube and a return pipe for maintaining circulating boiler water in the lower part of said chamber, a steam line leading from the top of said chamber for discharging steam therefrom into the steam space of the steam boiler, and means responsive to temperature changes in the steam in the said discharge pipe for controlling the amount of water in said chamber by limiting the passage of steam from the top of said chamber to the steam space of the boiler, said return pipe being heated by the superheated steam to produce convection circulation of the water going through the chamber from the boiler, and said tube leading from the water space of a steam boiler.

7. Fluid heat exchange apparatus comprising, in combination, a liquid evaporator having a pressure chamber in which the liquid and the generated gas are separated, a gas discharge line leading from the chamber, a superheater to which said line delivers the gas, a temperature regulator casing, a conductor directing the superheated gas through the casing, a superheated steam delivery pipe discharging steam into the conductor, means including a tube and a return pipe for maintaining a circulation of the liquid through the lower part of the regulator chamber, a superheated gas main leading from said conductor, and temperature responsive means causing the quantity of liquid in the regulator casing to change in accordance with temperature changes in the superheated gas, said return pipe being heated by steam in the delivery pipe for promoting convection circulation between the evaporator and said casing and said tube leading from a position beneath the liquid level of the evaporator.

8. In combination, a boiler having a steam space, a superheated steam pipe, a temperature regulator connected to said pipe and having a chamber beneath the normal water level of the boiler, two connections from the chamber to the water space of the boiler for maintaining a supply of water in the chamber, means for passing the steam from the pipe through the chamber while maintaining it

out of contact with the water therein, a connection from the upper part of said chamber to said steam space, a valve in said connection, and means to control operation of said valve by the temperature of steam leaving the regulator, said two connections including a part in which water circulation is promoted.

9. In combination, a boiler having a steam space, a superheated steam pipe, a temperature regulator connected to said pipe and having a chamber beneath the normal water level of the boiler, two connections from the chamber to the water space of the boiler for maintaining a supply of water in the chamber, means for passing the steam from the pipe through the chamber while maintaining it out of contact with the water therein, a connection from the upper part of said chamber to said steam space, a valve in said connection, and means to control operation of said valve by the temperature of steam leaving the regulator, one of said water connections being arranged to absorb heat.

25 10. In combination, a boiler having a steam space, a superheated steam pipe, a temperature regulator connected to said pipe and having a chamber beneath the normal water level of the boiler, two connections from the chamber to the water space of the boiler for maintaining a supply of water in the chamber, means for passing the steam from the pipe through the chamber while maintaining it out of contact with the water therein, a connection from the upper part of said chamber to said steam space, a valve in said connection, means to control operation of said valve by the temperature of steam leaving the regulator, one of said water connections absorbing heat, and a check valve in said heated water connection permitting flow to said water space but preventing flow therefrom.
